UNITED STATES PATENT OFFICE

WILLIAM L. BRYANT, OF SPRINGFIELD, VERMONT

MULTIPLE-SPINDLE GRINDING MACHINE OR THE LIKE

Application filed April 19, 1927. Serial No. 184,851.

This invention relates to grinding machines and the like particularly intended for rapid and accurate quantity production. To this end the machine is provided with a plurality of work holders and a plurality of tool spindles, the tools acting successively on the pieces of work held by the several holders which are stepped from one to the next operative position for the tools from and to a holder loading and delivering position. Each of the tools is intended to perform a part only of a single machining operation, each tooling operation completing the machining operation on one piece of work, and commencing the machine operation on another piece of work, any intermediate tools performing intermediate parts of the complete operation.

In the particular embodiments of the invention hereinafter described in detail by way of illustration of the invention without, however, intending in any way to limit the invention to any particular machine, the work holders are carried in a rotatable drum in which they are arranged in a circular series in what may be termed a headstock of the machine. The tools which in the embodiments shown are grinding wheels have their spindles arranged in similar series but with one position vacant to provide a loading and unloading station for the work in a head adjacent to one end of the drum carrying the work holders. Relative traversing motions between the work holders and the tool spindles are effected, in the present embodiment this being accomplished by so mounting the tool spindles that they may be traversed axially relative to the work, there being one work holder which is not in operative relation to a tool so that this holder is free during the tooling operations on work on each of the others to have a finished piece of work removed therefrom and a new piece placed in position.

The tool spindles are positioned between the headstock and what may be termed a tailstock, which in the embodiment shown, contains the traverse mechanism and certain of the mechanism for imparting rotary motion to the work holders.

Means are also provided for effecting a rela-

tive rocking about the axis of the series of work holders and tool spindles to provide feed and retracting motions to the tools relative to the work, and in the constructions herein shown and described the tool spindles are given this motion.

Means may be provided also for automatically truing the tools at predetermined times during the operation of the machine.

The provision of a plurality of work holders and a plurality of tools working simultaneously on the work held by these holders, the work progressing from one to a succeeding tool, presents marked advantages over the usual single work holder single tool arrangement. One of these is that it makes possible the use of tools each particularly adapted to the particular work it is called upon to perform. For example, the first tool of the series may be called upon to act on the relatively rough, hard skin of a casting. It can, therefore, be a tool particularly adapted for such service since it is not called upon for any other. Likewise the last tool may be particularly designed to provide a high finish and may indeed be a lap if desired, and may be adjusted so that it is not called upon in any case to remove any considerable amount of metal. Similarly the amount and character of work which any other tool is called upon to perform is the same for each piece of work. While the extent of movement of feed and retraction of each of the tools is the same, yet by adjustment, the amount of such movement effective to determine the depth of cut for any particular tool may be varied. Thus each tool may be made to take whatever depth or character of cut is desired without reference to any other and without re-setting of either work or tool. At each step by step, or indexing movement of the work holder relative to the tools, moreover, the desired complete operation on one piece of work is finished and a new piece is placed in position.

Indexing stops may also be provided so that the work in each of the holders may be finished to the same dimensions regardless of slight inaccuracies in construction of the machine or due to wear.

While the invention is particularly suitable for a machine for grinding plane internal work, it is not limited thereto, one embodiment herein shown being designed to grind the inner race surfaces of ballbearing outer raceway members.

For a more complete understanding of this invention, reference may be had to the accompanying drawings in which

90 Figures 38 to 41 are diagrammatic views illustrating relative positions of work grinding wheel and truing devices in different parts of the machine cycle.

Figure 42 is a diagram of control cams for the feed while the grinding wheel is in the position shown in Figure 38.

95 Figures 43, 44 and 45 are diagrammatic views showing successive positions of portions of the traverse control mechanism.

Figure 46 is a view similar to Figure 42 but showing the parts in different positions.

100 Figure 47 shows the truing device controlling mechanism.

In general the machine comprises a bed 1 supporting at one end what may be termed a headstock 2 and at the other end what may be termed a tailstock 3. Between the head and tailstock is positioned a tool holder 4 which as will later more fully appear is traversed between the head and tailstocks by a mechanism supported by the tailstock.

Work holding and driving mechanism

Within the headstock portion 2 is mounted for rotation about a horizontal axis extending toward the tailstock a work holder supporting drum 10 shown detached in Figures 14 and 15. This drum is provided with annular tapered bearing faces 11 and 12 mating corresponding surfaces of the headstock 2.

The larger end of the drum is provided with an annular shoulder 13 extending over the end 14 of the headstock, these parts being held in engagement with each other by means of a retaining ring 15 (see Figure 7)

115 having a flange portion 16 engaging the outer face of a worm ring gear 17 which rests against a shoulder 18 on the end of the drum.

The retaining ring 15 is resiliently held toward the headstock by means of screws 20 threaded into the headstock, and carrying,

in sockets 21 in the retaining ring springs 22, reacting between the bases of these sockets and the heads of the screws.

Arranged in circular series in the rotatable drum 10 are a plurality of rotatable work holders each journaled for rotation about a longitudinal axis therein. As shown best in Figure 13 each work holder comprises an outer sleeve portion 25 carrying at spaced points along its length inner ring members 26 and 27 of ball bearings 28 and 29. Beyond the ball bearings 29 the sleeve 25 has fixed thereto, as by threaded engagement, a chuck member 30. This chuck member 30 has an annular flange 31 supporting on its end face a ring 32 fixed thereto as by screws 33. This ring 32 has the outer end portion of its bore outwardly tapering as at 34 and cooperating with this bore are a plurality of work-engaging jaws 35. Each jaw is pivoted at its rear end as at 36 to a flange portion 37 at the outer end of a sleeve 38 slidable within the sleeve 25, the jaw members 35 being urged outwardly against the inner face of the ring 32 by means such as the spring pressed plugs 40. A locating plate 45 fits within the flange 31 and is provided with an annular abutment portion 46 against the outer face of which the inner face of the work to be ground may be held by the jaws 35. The work is shown in Figure 13 at W. Each of the jaws 35 has a lip portion 48 bearing against the outer face of the work and which during the operation of the grinding wheels thereon hold it firmly against the outer face of the abutment portion 46. The inner end of the sleeve 38 is shown as fixed as by a threaded engagement 50 to a sleeve 51, which is shouldered adjacent to its opposite end to receive the hub portion 52 of a flanged collar 53 which is fixed thereon as by means of the pin 53a. The adjacent end of the sleeve 25 is also threaded for the reception of a collar 55 which is fixed thereto in a similar manner by means of the threaded plug 56, there being a space between the collar 53 and the collar 55 for a purpose which will later appear. The sleeve 51 intermediate its ends has an external shoulder against which bears a ring 60 which provides an abutment on one end of a compression spring 61, the other end of which engages against a similar collar 62 having threaded engagement with the inner face of the sleeve 25. This spring presses the sleeve 51 and with it the sleeve 38 carrying the jaws to their inmost limits of motion; or to the left, as shown in Figure 13, so that the jaw members are brought into engagement with and hold the work firmly against the retaining plate. As will later more fully appear, at certain times in the cycle of operation, the collar 53 is given a motion in the opposite direction against the pressure of the spring 61, thus carrying the

jaws 35 outwardly and permitting their inclined rear faces 65 to slide over the faces 34 of the ring 32, the spring pressed plugs 40 then causing the jaws to separate to withdraw their lips 48 from over the end of the work.

Within the sleeves 51 is slidable a bar 70, one end of which is threaded into the shank portion 71 of an ejector member having a head 72 provided with a tapered work centering end 73. This work centering end may pass into the work as it is presented thereto, thus holding it centered until the jaws may engage it and move it back against the abutment plate, while when the jaws are moved to release the work and the ejector is pushed forwardly, the finished work is ejected by it from the chuck. The bar 70 is held from rotation relative to the sleeve 51 by any suitable means, as herein shown the screw plug 54 extending into a key slot 75 in the bar 70. This bar may be given an axial motion independent of the axial motion of the sleeve 51 in so far as is permitted by the engagement of the rear end of the head 72 with the forward end of the sleeve 38 and for this purpose a spool shaped member 76 fixed thereto at its outer end is shown. The sleeves 25 and 51 are also held against relative axial turning, for this purpose the plug 56 for retaining the collar 55 in position being shown as extending into a key slot 78 in the hub 52.

As shown best in Figure 12 the ball bearings 28 and 29 are held in tapered bearing bushings 80 and 81 fitted in mating tapered portions 82 and 83 in the drum head. Each bearing bushing 80 is held in position by a retaining ring 84 threaded on its smaller end and each bushing 81 is held in its proper position by an adjusting screw 85.

The outer face of each of the bushings 81 and the inner face of the chuck 30 may be provided with interfitting annular grooves and shoulders to prevent dust from the grinding wheel finding its way to the ball bearing. Each of the sleeves 25 extends through an enlarged hole 90 in the ring gear 17 and outwardly thereof carries journaled thereon a gear 92. This gear 92 has an internal tapered clutch face 93 for cooperation with a mating face on a clutch collar 94 slidable on the sleeve 25 but keyed against rotation relative thereto as by means of the key 96. As best shown in Figure 13, this clutch collar is normally pressed into clutching engagement with the collar 92 as by means of spring pressed plugs 97 seated in sockets 98 therein and reacting against the collar 55 fixed to the end of the sleeve 25. This clutch element may be moved out of clutching relation, as will later appear, by means engaging the inner face of an annular flange 99 at the outer end of the collar 94.

As herein shown six work holders con-

structed as shown in Figure 13 are employed, arranged in circular series in the drum 10 and each of the gears 92 thereon are arranged to mesh with a central gear 100 (see Figure 6). Of course a different number might be used if desired. The gear 100 is fixed to an actuating shaft 101 and extends centrally through the drum 10, being journaled at one end on a ball bearing 102 carried by a ring 103 set into the outer end of a central bore 104 of the drum 10 and its other end, as shown in Figure 20, having a ball bearing 105 carried by a plate 106 closing the outer end of the hollow tailstock portion 3. Beyond the tailstock a belt pulley 110 is shown as fixed to the shaft 101 by which it may be rotated, thus to drive each of the gears 92 and through their respective clutch mechanisms when these are in engagement, to rotate each of the work holders regardless of the angular position of the drum 10.

Indexing mechanism

Means are provided by which the drum 10 may be rotated step by step to bring the work holders successively into operative relation to each of the tools. This is accomplished by rotating the drum through the ring gear 17. Referring to Figure 9, 120 indicates a shaft extending in the plane of the ring gear 17 and journaled in bearings 121 in a bracket 122 fixed to one end of the bed 1. This shaft 120 is mounted for axial as well as rotatable motion and is provided at its inner end with a ball thrust bearing comprising a ball 123 seated in a suitable socket therein and bearing against a hardened pin 124. Opposite to the pin 124 is a wear piece 125 fixed to the end of a plug 126 slidably mounted in the bracket 122 and pressed toward the shaft 120 by means of a coil spring 127 reacting between the opposite end of the plug 126 and a cover plate 128 at one end of the bracket 122. When the spring 127 is permitted to move the shaft endwise it brings a worm 130 meshing with the ring gear 17 into central meshing relation therewith. This shaft 120 has keyed thereto within the opposite end of the bracket 122 a clutch collar 132 and mating with this clutch collar when the shaft 120 is in such position that the worm has central meshing relation with the worm gear 17 is a clutch collar 133 which has a shoulder portion 134 limiting its axial motion relative to the clutch collar 132 by impingement on the end of the bracket 122. When the shaft 120 is moved against the action of the spring 127, or to the right in Figure 9, so as to bring the worm 130 out of central meshing relation with the ring gear 17, the clutch collar 132 is out of clutching relation with the collar 134. Keyed to the collar 133 is a sprocket gear 135 which may be driven by means of a silent chain or other suitable

means from a similar gear 136 carried by a shaft 137.

The clutch collar 133 is normally held pressed toward the end of the bracket 122 by means of a spring 140 reacting between its outer end and the adjusting and check nuts 141 and 142 threaded on the outer end of the shaft 120. The shaft 120 is mounted to turn in such a direction that when the worm 130 is in central engagement with the gear 17, this gear 17 will turn as long as it is permitted to do so without great obstruction. It can, however, be held against movement, whereupon continued rotation of the shaft 120 causes the worm teeth to act as a nut, producing axial motion of the worm and consequently axial motion of the shaft 120 against the action of the spring 127 until the clutch collar 132 is brought out of engagement with the clutch collar 134.

Means are provided for stopping the rotation of the worm gear periodically when each of the work holders is in operative relation to one of the tools. For this purpose the drum 10, as shown best in Figures 7 and 9, is provided with stop pins as 150. As shown more particularly in Figure 7, each of these pins comprises a central cylindrical portion 151 bridging a slot 152 extending inwardly from the periphery of the drum (see also Figure 15). At either side of this cylindrical portion, each pin has tapered bearing portions as 153 and 154 bearing in mating sockets in the drum 10. Each of these pins is also provided with a threaded head 155 provided with a screwdriver slot which head bears in a threaded socket portion 156 in the outer face of the drum 10. Cooperating with each of the stop pins in turn is a latch member 160 pivoted at 161 in the headstock portion 2. This latch 160 may be moved up into the path of each of the stop pins within the corresponding slot 152 at suitable times, this being accomplished by means of a thrust bar 162 (see Figures 1, 6, 9 and 12) having a head portion 163 pivotally connected to the latch 160. The lower end of this thrust bar is pivoted to one arm of a lever 164 fulcrumed at 165. The other end of this lever carries a cam roll 166 actuated by a cam 167 carried by a shaft 168. This shaft 168 as shown is driven from clutch collar 134. For this purpose the clutch collar 134 has keyed thereto a gear 170 meshing with a gear 171 on a worm shaft 172. This worm shaft carries a worm 173 meshing with a worm wheel 174 carried by a shaft 175 which has fixed thereto a beveled gear 176 meshing with a similar gear 177 fixed to the shaft 168.

When the drum in its rotation approaches an indexing position, the latch 160 is moved by the cam 167 to bring its end into the path of movement of one of the stop pins 150. As soon as the stop pin strikes this latch member further rotation of the ring gear 130

17 is stopped, whereupon continued rotation of the shaft 120 causes its axial movement until the clutch collar 132 is moved out of driving relation with the clutch member 134. 5 The action of the spring 127 imparting a peripheral thrust to the worm gear holds the stop pin against the end of the latch and so retains the drum in its indexed position. In order that adjustments for wear or machine 10 inaccuracies may be made so that the stopping position at each indexing may be made accurate, the cylindrical portion 151 of each stop pin may be formed eccentric to the axis of the pin as shown in Figure 8. Thus by 15 turning the stop pin slight adjustments of the stopping position may be made.

When it is desired to effect the next indexing movement it is necessary to disengage the latch 160 from the stop pin and in order 20 to facilitate this as well as to reduce wear between the latch end and the stop pin, since the accuracy of stopping position depends on the accuracy with which these elements function, means are provided for giving a 25 reverse rotation to the drum sufficient to relieve the pressure between the stop pin and the latch before the latch is moved out of obstructing position. For this purpose a short shaft 180 journaled in the bracket member 122 transverse to the shaft 120 is provided with an eccentric portion 181 carrying on 30 one end of the worm 130 to give an axial movement to the shaft 120 against the pressure of the spring 127, thus to turn the ring gear 17 slightly in a reverse direction to its 35 indexing motion. To accomplish this, the shaft 180 has fixed thereto an arm 182 having a cam follower 183 clamped thereon and having an inclined face which is wiped by a cam element 184 having a mating inclined face and carried by a collar 185 fixed to the 40 shaft 168 in such a manner that the arm 182 is rocked to the necessary extent to produce the required axial movement of the shaft 45 120. As soon as this axial movement has been effected the latch 160 is retracted, and the cam element 184 then passing beyond the follower 183, permits the spring 127 to move the shaft 120 axially to clutch the shaft 120 for rotation until the rotation of the drum is stopped by impingement of a succeeding 50 pin on the latch 160 which is raised again in time to cause such action.

55 Work loading and unloading

As has already been mentioned, one station occupied by each of the work holders in turn is reserved for removing finished work and 60 inserting work to be operated upon. For the purpose of automatically supplying the pieces of work to the tool holders a magazine feed has been provided. Referring to Figures 1, 2 and 3, an inclined trough 200 is 65 shown as attached to one side of the head-

stock 2, a rod 201 carrying at its outer end a chute support 202 supporting the upper end of the chute while the lower end is carried by a support 203 carried at the upper end of a post 204 mounted vertically in a bracket 205 fixed to the headstock. 70

The pieces of work W, which in the present instance comprise ring shaped members, are stacked on edge in this chute as shown in Figure 1. The lower end of this chute leads to a vertical guideway formed by spaced guiding elements, one comprising a bracket 206 against which the pieces of work impinge as they leave the lower end of the chute 200 and the other a guide plate 207. The bracket 206 is provided with a supporting portion 208 (see Figures 2 and 3) arranged to support in a downwardly inclined direction toward the loading station, a second chute 210. This chute is in a plane at right angles to the chute 200 so that the pieces of work are arranged on edge and in alinement as shown by the dotted lines in Figure 3. The outer end of the bracket 206 with its extension 208 is adjustably supported on a bar 212 carried by the bracket 205 and the lower end of the extension 208 is adjustably supported by means of an adjusting screw 215 (Figure 3) on a bracket 216. This bracket 216 also has means for supporting an unloading chute 218 85 downwardly and outwardly inclined, which conducts the finished pieces of work away from the loading and unloading station and into which they fall when ejected by the action of the ejecting projector 72. 90

The inner end of the chute 218 is positioned adjacent to the outer end of the chuck of each work holder as it comes into the unloading and loading position, while the chute 210 for supplying the new pieces of work is positioned outwardly of the chute 218 as shown more particularly in Figure 22. This bracket 216, as is shown in Figures 1 and 22, has an enlarged cylindrical horizontal upper portion 220 bored out in line with the axis of the chuck when positioned at the loading and unloading station. Within this bored out portion are spaced bearing bushings 221 within which is slidably mounted a plunger 222. The inner end of this plunger has fixed thereto a loading ram 223 having an end portion 224 of reduced diameter defined by an annular shoulder 225. The lower end of the chute 210 is turned upwardly as at 228 so as to position each piece of work in succession directly in line with the ram 223 so that as this ram is pushed toward the chuck by a movement of the plunger 222 the reduced portion 224 threads into the hole in the work and the shoulder 225 thereon carries it over the discharge chute 218 and into the chuck. The reduced portion 224 is somewhat shorter than the thickness of the work so as to permit the work to be forced up on to the tapered centering end 73 of the ejector plunger, thus 110 115 120 125 130

to center the work in the chuck so that the clamping jaws 35 may then be operated to fix the work in the chuck. The plunger 222 is thereupon withdrawn into the position shown in Figure 22 so that it will not interfere with the ejection of the finished work when the next chuck in the series is first presented to the loading station. The plunger 222 is given its proper reciprocating motions by means of a cam 230 carried on a shaft 235, the cam acting on a follower 236 carried on one arm of a bell crank lever 237, the other arm of which carries a follower roll 238 bearing between spaced collars 239 fixed to the outer end of the plunger rod 222. The shaft 235 is driven in time with the other mechanisms of the machine in a manner which will later be described.

Means for effecting the desired reciprocating motions of the centering and ejecting mechanism in each chuck so that finished work may be ejected and new work be centered and fixed therein will now be described. As has already been described the rod 70 which carries the ejector and centering member is provided at its outer end with a spool shaped element 76. Between the flanges of this element rides a cam follower at the upper end of a lever 245 fulcrumed at 246 the opposite end of which carries a cam follower 247 riding on a cam 248 fixed to the end of the shaft 168. The lever 245 is normally held with its follower against the cam 248, as by means of a spring 264 fixed at one end thereto and at its other end to the headstock portion 2. The clamping jaws are moved bodily to release the work as before described by means engaging the collar 53. This means comprises a cam follower 250 carried at the upper end of a lever 251 fulcrumed at 252 and having at its other end a cam follower 253 controlled by a cam 254 also fixed to the shaft 168.

As during the ejecting and insertion of the work the rotation of the chuck should be stopped, means are also provided for retracting and so holding the clutch collar 94 from clutching relation with the gear 92. This is effected through an arm 260 having a cam follower engageable on the inner face of the flange 99. This arm 260 is also fulcrumed at 252 and has an extension 261 riding on an edge cam 263 also fixed to the shaft 168. The upper ends of each of these arms or levers are so positioned that the elements with which they engage are brought into cooperative relation therewith whenever a work holder is brought to unloading and loading relation, but so as not to interfere with rotation of the work holder carrying drum in any manner. Thus when each work holder is brought into its leading and unloading position its rotation is stopped by release of its clutch element 94 from its driving gear 92 and the clamping jaws are actuated to release the work which is then pushed out of the chuck by reciproca-

tion of the ejector, the finished work falling into the chute 218 which conducts it away from the work holder. The loading ram then threads through a new piece of work in the lower end of the chute 210 and presents it to the centering end of the ejector plunger and the two move into the chuck bringing the work toward the abutment plate whereupon the clamping jaws are actuated to clamp the work in its centered relation against the abutment plate. The loading ram then retracts and the clutch 94 is permitted to again engage the gear 92 so that the work is rotated.

Tool mounting and rotating mechanism

Journaled in a central opening in the work holder drum and surrounding the driving shaft 101 is a hollow tool bar 300. As shown best in Figure 21, this tool bar 300 is provided with an externally tapered portion 301 on which is carried the tool carrier 4. This tool carrier comprises a generally cylindrical shaped head having a cut away portion arranged opposite to the unloading and loading station, the cut away portion being of sufficient size to permit rocking of the tool carrier about the central axis of the drive shaft 101 for a sufficient distance to effect tool feed and retracting motions without interfering with the work loading and unloading mechanism which extend into or through this portion. This tool carrier supports a series of tools in circular arrangement, corresponding to the arrangement in circular series of the work holders except that there is one less tool than there are work holders so as to leave the work unloading and loading station without a tool. Six work holders being shown in the present embodiment there will, therefore, be five tools. As herein shown also each tool comprises a grinding wheel.

As shown more particularly in Figure 21, each grinding wheel, as at 302, is carried at the end of a tool shaft 303 journaled in a bearing member 304 fixed in any suitable way in the tool carrier 4. At each tool position the tool carrier is shown as divided into two compartments 305 and 306. The bearing member 304 extends through the compartment 305 and a high speed motor 307 is mounted in the compartment 306. As shown this motor has an end flange portion 308 bearing over the outer end of the compartment 306, this being fixed to the head 4 by means of a cover member 309 bolted thereto. Within this cover member is shown positioned a ventilating fan 310 fixed to the motor shaft and which acts to force air through the compartment 306 thus to cool the motor, the compartment having an opening 311 through which the air may escape. The motor shaft 312 is connected to the shaft 303 preferably through a floating or universal coupling as at 313 so as to provide for any inaccuracy in alinement between the shafts 303 and 312, it being impor-

tant that the shaft 303 should run accurately and free from vibration in its bearing 304 for high accuracy of work. The tool holder 4 is held in position on the hollow rod 300 by any suitable means, as herein shown a clamping collar 315 being threaded on the rod 300 adjacent to the small diameter portion of the tapered bearing 301, this collar acting to hold the tool head 4 in fixed relation to the rod 300. 10 Suitable leads (not shown) may extend from each of the motors to a controller of any suitable type by which the rotation of the motors and the consequent rotation of the tools may be controlled.

15 *Tool traversing mechanism.*

As shown in Figure 20, the opposite end of the hollow bar 300 which carries the tool head 4 to that journaled in the work holder-carrying drum 10, is mounted in a tapered bushing 400 in the headstock 3. Besides being permitted a rocking motion about the axis of the shaft 101, this bar 300 may be reciprocated axially. For this purpose it is shown as provided with circular rack teeth 401 within the tail-stock 3, these rack teeth being in mesh (see Figures 17 and 20) with a pinion 402 fixed to a feed shaft 403 extending through the tailstock to the front face of the machine 25 where it may be provided, if desired, with a hand wheel 404 by which it may be turned so that the tool holder may be reciprocated axially by hand to bring the tools into and out of operative relation to the work when this is 30 desired. Means are provided, however, by which such reciprocation is effected by power to bring the grinding wheels into and out of operative position and while grinding is taking place, means, as will later appear, being 35 provided by which the tool head may be rocked about its central axis to provide feed and retractive movements to the tools relative to the work. As will also more fully appear, means are provided by which the grinding 40 wheels may be trued when desired. When 45 the tools are in operative relation with the work, a lengthwise traverse between the tool and the work is desirable even when the wheel is of sufficient axial length to engage the entire 50 length of the whole surface of which is being acted on by the wheel and such traversing movement while the wheel is in engagement with the work should be relatively rapid. Tool truing traverses should, however, 55 be relatively slow. Provision is therefore made by which a relatively rapid speed of traverse between the tool and the work is effected when the tool is in contact with the work and a relatively slow speed when the tool is being dressed or trued. For this purpose the shaft 403 has fixed thereto a worm gear 410 with which meshes a worm 411 keyed to a sleeve 412 journaled on a shaft 413 (Figure 20). The ends of the sleeve 412 are 60 formed with clutch faces with which coact

alternately mating faces on a pair of clutch collars 414 and 415. Outwardly of the collar 414 the shaft 413 has fixed thereto a collar 416. Outwardly of the clutch collar 415 the opposite end of the shaft 413 has fixed thereto a spool shaped collar 417. The sleeve 412 and the clutch collars 414 and 415 are journaled in a pair of sleeves 418 abutting opposite sides of the worm 411. These sleeves 418 are held in axially adjusted position by means of the adjusting threaded plugs 422 positioned in inclined arrangement in sockets in a casing portion 420 and having their inner ends engaging inclined faces of perforations 423 in these sleeves. It will be noted that each of these sleeves 418 extends outwardly beyond an end portion of the casing 420 and journaled on these end portions and abutting the ends of the casing are the gears 425 and 426. These gears are keyed to rotate the clutch collars 414 and 415, respectively, by means of pins 427 and 428 riding in slots in the outer end portions of these clutch collars so that rotation imparted to either of the gears 425 or 426 will drive the corresponding clutch collars 414 and 415 either of which may be made to impart rotation to the worm 411, depending on the axial position of the shaft 413. This axial position is controlled by means of a bell crank lever 430 (see Figure 16) having a pair of cam rolls 432 engaging in the groove of the spool shaped collar 417 (see Figure 20). This bell crank lever 430 is actuated to throw the shaft from one axial position to the other to alternately bring the clutch elements 414 and 415 into driving relation with the worm 411.

Means are provided by which the gear 425 is driven in one direction and the gear 426 in the opposite direction so that by moving the bell crank lever 430 the direction of rotation of the worm 411, and consequently of the traversing shaft 403, may be reversed. Not only is the gear 426 driven, but it is also arranged to be driven at either of two different speeds.

The mechanism for driving the gears 425 and 426 is illustrated diagrammatically in Figure 20a in which, for purposes of illustration, a part of the mechanism has been shown twice. The gear 426 meshes with a gear 435 journaled on the shaft 436 and this gear meshes with a gear 437 fixed to a countershaft 438 (see Figure 17 and also Figure 20a where this shaft is shown part at the top and part at the bottom). Also fixed to the shaft 438 is a gear 439 which meshes with a gear 440 also journaled on the shaft 436. The gear 440 may be clutched to rotate with the shaft 436 by means of the clutch collar 441 slidable but non-rotatable thereon. When this collar is in clutching relation with the gear 440 rotation of the shaft 436 causes the gear 440 to rotate, which acts through the gears 439 and 437 on the shaft 438 and the gear 435

to rotate the gear 426. The clutch 441 may be disconnected from the gear 440 and thrown into engagement with the gear 442 also journaled on the shaft 436. This gear 442 meshes with a gear 443 on the shaft 438 and the gear 444 also on the shaft 438 meshes with the gear 425. It will be noted, however, that the gear ratio between gears 442 and 443 is smaller than that between the gears 440 and 439 so that when the shaft 438 is rotated by the driving of the gear 442 instead of the gear 440, the rotation of the shaft 438 is slower than when it is rotated by the gear 440. Consequently when the clutch collar 441 is thrown 15 to the left, as shown in Figures 20 and 20a the gear 426 is driven at its slower speed and when this clutch collar is thrown to the right it is driven at its highest speed. It will likewise be seen that the drive imparted to the 20 gear 436 is opposite in direction to that of the gear 425, due to the fact that there is one more gear in the train leading to the gear 426 than there is in the train leading to the gear 425.

The shaft 436 is therefore the main drive 25 shaft for this mechanism, and as shown best in Figures 17 and 20, this is positioned on the same horizontal plane as the shaft 413. The shaft 438 is in effect a countershaft, which is arranged above the plane of the shafts 413 30 and 436.

In order that the traverse of the tools may be effected by hand without reference to the power traverse the worm 411 is so mounted that it can be raised out of contact with the 35 worm wheel 410. For this purpose the casing 420 in which the shaft 438 and the sleeves 418 are journaled is pivotally carried by the drive shaft 436.

When it is desired to raise the casing 420 40 to bring the worm 411 out of mesh with the worm gear 410, this may be done by raising a hand lever 510 fixed at its upper end to the casing. This lever is normally yieldingly held in its lowered position, holding the worm 45 411, in mesh with the worm gear, by means of a spring pressed pin 511 seated in a socket therein and engaging a depression 512 in the tailstock portion when the lever is lowered.

The shaft 436 is arranged to be driven from 50 the work holder drive shaft 101. For this purpose it is shown in Figures 16 and 20 as provided with a gear 450 frictionally held to a tapered collar 449 carried thereby, this 55 gear meshing with a gear 451 keyed to the shaft 101. The clutch collar 441 is arranged to be thrown from one to the other of its positions at suitable times in the cycle of operations of the machine, for which purpose it has engaged in a peripheral groove therein 60 a roller 452 carried by a bell crank lever 453. This bell crank lever is arranged to be given a quick throw in opposite directions to throw the clutch collar from one to the other of its positions, this being done by means of 65 a snap action mechanism which may be re-

ferred to as a "load and fire" mechanism. The outer end of the arm of the bell crank lever 453 is provided with a pin 454 having a conical end with which coacts the mating conical end of a spring pressed pin 455 seated in the end of an arm 456. This arm 456 is fixed to a shaft 457 which carries an arm 458 having a cam follower 459 which may ride through a cam slot 460 in a cam arm 461 clamped to the shaft 403. As this shaft is oscillated to give the transversing movements in opposite directions to the tool carrier, the cam follower 459 engaging in the slot 460 is rocked, thus rocking the shaft 457 and causing the arm 456 to rock so as to bring the conically pointed pin 455 across the end of the pin 454. As soon as the point of this pin 455 passes over the point of the pin 454 in either direction, the inclined engagement of these pins causes a wedge action to be imparted to the arm 453 so that the spring action of the spring pressed pin 455 acts to throw the arm 453. This causes the mechanism to be put alternately into its slow and high speed traverse movement. Similarly 90 the bell crank lever 430 is thrown at suitable times by a "load and fire" mechanism to effect a reversal of the direction of traverse. The horizontal arm of this bell crank lever 430, as shown in Figure 16, carries the fixed 95 conically pointed pin 470 which is acted upon by the spring pressed conically pointed pin 471 in an arm 472. This arm is fixed to a shaft 473 which carries forwardly of the casing 420 a block 474. Pivoted to this block on a pin 475 is the U shaped upper end 100 476 of a hand lever 477. Lateral swinging of this lever 477 causes rocking of the shaft 473 through the engagement of the side flanges 478 of the U shaped portion on the 105 block 474, and results in rocking the arm 472 to throw the bell crank lever 430. Besides pivoting motion in this direction the lever may swing about the pin 475 at right angles thereto forwardly and rearwardly. It is 110 normally held in its substantially vertical position shown in full lines in Figure 17 by means of a spring 480 surrounding a screw 481 passing through a hole in the lever 477 and threaded into the block 474, this spring 115 reacting between the head of this screw and a washer 482 bearing on the outer face of the lever 477.

As shown best in Figure 17, the worm wheel 410 is provided with an annular slot 120 490 of T cross section in its outer face and within this slot may be adjustably positioned three abutment pins 491, 492 and 493. The hand lever 477 is provided with an inwardly extending finger 495 which may be struck by these pins 491, 492 and 493. It will be noted 125 that the pins 492 and 493 are relatively close together, but as shown more particularly in Figure 16a, the pin 492 is shorter than either of the pins 491 and 493. In either the full 130

line position of the lever 477 as shown in Figure 17, or the dotted line position swung outwardly about the pin 475 as a center, the pins 493 and 491 are in position to strike the 5 finger 495 of the lever 477, thus to effect the throwing of this lever and the rocking of the shaft 473 to effect reversal of the direction of rotation of the shaft 403. The pin 492, however, is so short that it will not strike the 10 finger 495 when the lever 477 is swung forwardly in the dotted line position of Figure 17, but it will strike this lever when it is in its vertical or full line position shown in Figure 17. When the lever is in its vertical position 15 a short traverse in opposite directions of the tool head is produced, this corresponding to the working position for the tools. When the lever 477 is swung outwardly a longer traverse is produced, this being the traverse 20 for removing the tool from the work and for returning it into its farthest operative position. The particular sequence of these operations will be more particularly described later.

25 When it is desired that the longer traverse should be made, this lever is swung outwardly to the dotted line position in Figure 17 and for this purpose a bell crank lever having a wide face 496 is journaled at 497 on a 30 bracket 498 fixed to the bed 1 of the machine, this bell crank lever being of sufficient width to engage the inner face of the lever 477 throughout the range of its swinging motion about the shaft 473 as a center. The substantially horizontal arm 499 of this lever 35 may be pressed downwardly by means of an adjustable abutment bolt 500 carried at one end of a lever 501, this lever having a cam follower 502 at its opposite end engaging 40 a cam 503 fixed to the shaft 235.

Tool feeding mechanism

Beside being given a traversing motion, the tool head 4 is caused to rock, together with 45 the bar 300, about the axis of the shaft 101 as a center. This rocking motion moves the tools simultaneously in paths eccentric to the axes of rotation of the several work holders thus to feed or retract the tools relative to 50 the work. To effect such motion the tool carrier 4 has fixed to its rear lower portion, as shown in Figures 10 and 11, an arm 550, the lower end of which is extended forwardly into a recess 551 in the back portion of the 55 machine bed 1 and to this forward end is fixed a block 552 which together therewith define a groove in which is held a wear piece 553 which when the tool carrier is traversed moves longitudinally in engagement with a 60 roller 554 journaled on the pin 555 at the rear end of a feed slide 556. This feed slide is mounted for axial sliding movement in a tapered bearing 557 positioned in a vertical partition 558 in the bed portion 1, being 65 keyed thereto as by means of a key 559 so as to prevent rotation. Forwardly of this bearing portion the slide 556 has a threaded portion 560 which engages with the internal threads of a sleeve 561. This sleeve is journaled in a bushing 562 extending through a 70 boss 563 projecting forwardly from the bed portion 1. The rear end of the sleeve 561 is formed with an annular shoulder 564 engaging over the rear end of the bearing bushing and forwardly of the boss 563 it has 75 journaled thereon a worm wheel 565. The worm wheel and the shoulder 564 hold the sleeve 562 against axial movement within the boss, the worm wheel 565 having a hub portion 566 with which is engaged at its outer end the hub 567a of a wheel 567 keyed to the sleeve 561 and held in position thereon by means of the nut 568, which when turned up against the outer face of the wheel hub forces it into frictional engagement with the hub 80 566 of the worm wheel 565, whereupon turning motion imparted to this worm wheel will act to produce lengthwise traverse of the feed slide 556. By loosening the nut 568 the wheel 567 may be turned by hand as by means 85 of the handles 569 without turning the worm gear 565. The forward end of the feed slide 556, as at 570, is journaled in a portion of the sleeve 561. By rotation of this sleeve, it is evident that the feed slide may be moved 90 axially due to its threaded engagement with the sleeve. Journaled on the hub portion 566 of the worm wheel 565 and the hub portion 567a of the wheel 567 is a frame 575, the upper end of which is formed with a bearing 95 portion 576 (see Figure 18) for a shaft 577. This shaft is arranged at an angle to the plane of the worm wheel 565 but has fixed thereto a worm 578 engaging with this wheel. This worm 578 is held up snugly against the 100 bearing 579 by means of a spring 580 reacting between a washer 581 on the adjacent face of the bearing 579 and a collar 582 fixed to the shaft 577. Adjacent to the opposite end of the bearing portion for this shaft the frame 105 575 is provided with a socket 583 within which the shaft 577 has journaled thereon a pinion 584. This socket also has a guideway for a rod 585 having threads thereon which act as rack teeth with the pinion 584. Below 110 the bearing portion 576 the frame 575 has a bearing 586 for the rod 585. Above this bearing the rod 585 has a nut 587 engaging its threads and between this nut and the bearing portion 576 is positioned a coil spring 588 115 which normally acts to hold the nut 587 against the upper face of the bearing 586. Reciprocation of the rod 585, it is evident, will thus rotate the pinion 584. This pinion, as shown in Figure 18, has an integral hub 120 extension which is enlarged at its outer end as at 590 to form a ratchet wheel 591 (see also Figure 19) which is seated within a socket portion 592 in the inner face of a disk 593 pinned or otherwise fixed to the shaft 577. 125

Riding in a hole 594 in the disk 593 is a plug 595 which is pressed inwardly by a spring 596 into contact with the ratchet teeth of the ratchet wheel 591, the spring 596 reacting between the outer end of the plug and a threaded plug 597 closing the outer end of the hole 594. This plug 595 is so positioned that on the upward motion of the rod 585 imparting rotation to the pinion 584 in one direction 5 this pinion is coupled to impart rotation to the shaft 577 thus to rotate the worm wheel 578 and worm wheel 565, and when the nut 568 is tightened, to impart feed motion to the feed slide 556. When the rod 585 is moved 10 downwardly by the action of the spring 588, the pinion 584 turns idly on the shaft 577, being permitted to do so by the ratchet mechanism comprising the ratchet wheel 591 and its cooperating spring pressed 15 plug 505, so that no rotation of the worm wheel 565 is produced. Means are provided for raising the rod 585 to a definite position at suitable times to impart this feed motion, this comprising a cam 600 journaled on the 20 shaft 235 and actuated by gearing which will be described later in connection with the truing mechanism so as to advance the tool after each truing operation. The amplitude of this tool advance to compensate for the 25 truing of the grinding wheels and produced by the upward motion of the rod 585 is determined by the position of adjustment axially thereof of the nut 568 which determines the extent to which the rod 585 may be pressed 30 downwardly by the spring 588 and thus the extent of motion necessary to raise it to the definite position determined by the cam 600. In the normal operation of the machine it is intended that when the several grinding 35 wheels are brought into operative relation to the work each cuts to the desired size, the finishing wheel cutting or polishing to the exact finish size of the work, while the preceding wheels cut to definite sizes less than 40 the final cutting depth. In order to maintain the sizing constant at each spindle therefore, it is necessary to advance the wheels only as they wear or are made smaller by the truing operations, and this advance is that 45 produced by the upward motion of the rod 585.

In order, however, that the indexing of the work from one to a succeeding grinding position may be permitted, the wheels are retracted from their normal working positions in a direction opposite to the compensating feed and are then withdrawn axially of the work. The work is then indexed, and the grinding wheels are then returned to their 50 cutting positions axially of the work and are brought up to the work axially thereof and caused to traverse the work. For the purpose of imparting such motions of feed and retraction of the wheels relative to the work 55 for indexing and independently of the feed

motion which compensates for truing of the wheels, the frame 575 is provided with a downwardly extending arm 601 having a cam roller 602 at its lower end which rides on a cam 603, also fixed to the shaft 235. This cam has a high portion 605 which determines the depth of feed of the tools, this cam portion terminating in an abrupt shoulder 606 which permits the tools to be drawn back by means of the spring 607 reacting between the frame 575 and a fixed portion of the machine bed, it being understood that by this rocking motion of the frame the worm 578 through its engagement with the worm wheel 565 imparts rocking motion thereto and thus advances or permits retraction of the grinding wheels relative to the work depending on its direction of rocking. Whenever it is desired to true the wheel, the retracting motion of the tools is to a less extent so that the tools may be traversed in contact with the truing devices, the extent of withdrawal of the tools during non-truing strokes being to a greater extent so that the tools do not contact with the truing mechanism as they are traversed. For this reason the cam roll 602 is extended laterally beyond the face of the cam 603 so as to be stopped at suitable times by a cam portion 610 which extends to a greater distance from the axis of the shaft 235 than the low part 611 of the cam 603 beyond the shoulder 606, thus to prevent the arm 601 from being rocked backwardly by the action of the spring 607 to as great an extent as if the cam 610 were not present. As in the normal operation of the machine truing is usually unnecessary at each withdrawal traversing stroke, provision may be made by which the cam portion 610 may be brought into operative position at more extended time intervals. In order that this may be done this cam is shown journaled on the shaft 235 and provided with a hub key slotted at its inner end to receive the pin 612 which it is made fast to the cam 600 which is made fast to a gear wheel 613 as by screws 631 also journaled on this shaft. The gear 613 meshes with a pinion 614 journaled on a stub shaft 615 and fixed to the pinion 614 is a large gear 616 which meshes with a pinion 617 keyed to the shaft 235. By this means the rotation of the cam member 610 is at a slower speed than the rotation of the shaft 235 so that it comes into operative relation with the cam follower 602 at intervals greater than the time of a single rotation of the shaft 235. The cycle of operations is thus as follows: The grinding wheels are traversed into the plane of the work and are then fed laterally into contact therewith. During this contact their reciprocation continues. They are then retracted and then moved axially away from the work, the last part of this retraction and the first part of the next advance being at the slow speed. At suitable intervals the extent 115

of retraction is less than normal so that during the slow reciprocation they are in contact with the truing devices. As they again approach the work the slight feed motion to 5 compensate for wheel wear is effected as hereinbefore described.

Wheel truing mechanism

Referring to Figures 3, 4, 5 and 7, 700 indicates a ring shaped truing device carrier member rotatably carried by the headstock between the work holders and the tool carrier 4. As shown in Figure 7, this member has a marginal rib 701 fitting in an annular groove 702 in the inner end face of the headstock, being retained in this groove by a retaining ring 703 made fast to the headstock end at suitable intervals as by means of screws 704. This disk member is cut away at one portion, 10 as at 705, as shown in Figure 3, opposite the loading and unloading station for the work holders. It may be adjusted through a small arc relative to the headstock by means of a lever 706 journaled at 707 on the headstock, one arm of which as at 708 engages in a notch 709 of the ring member 700. The opposite arm 710 of this lever has an abutment screw 711 threaded therethrough bearing on a lug 712 on the side of the headstock. 15 This ring member 700 is provided with a plurality of spaced holes 715 therethrough through which the grinding wheels pass during the traverse of the grinding wheels from and to grinding position, these holes 20 being of sufficient size to permit the wheels to pass therethrough throughout their full range of feed motion. Adjacent to each of these openings the ring member 700 is provided with a radially arranged 25 outwardly directed flange 716 through which passes an inclined adjusting screw 718 (see Figure 4), the inner end of which bears against the rear end of a diamond holder or truing device 720 which is held in 30 a slot or recess in the outer face of the ring member with its inner end projecting beyond the margin of the hole 715 adjacent thereto, the truing device being held in adjusted position in its guide slot by means 35 of a clamping bolt 721. The diamonds or truing devices are adjusted to project sufficiently far beyond the edge of the hole 715 so as to engage and true the tool during its retractive movement from operative relation 40 to the work whenever the cam 610 is in position to prevent the full retracting movement caused by the rocking of the worm gear 565, through the action of the spring 607. When the cam 610 does not interfere with 45 this retraction, the tools are rocked to such an extent that they do not engage the wheel on their retracting traverse. This action is shown diagrammatically in Figures 23 to 26 for a single tool. In Figure 23 the wheel 302 50 is shown as projected through the corre-

sponding opening 715 of the ring 700 toward operative relation with the work W. In Figure 24 it is shown as moved further in the same direction. In Figure 25 the tool is shown as traversed still further in the same direction, but has been brought into working engagement with the inner face of the work by the rocking of the tool holder 4. While in this position and during its feed laterally against the work, it is traversed at the rapid speed. When the cut has been finished the wheel is moved away from the inner face of the work by reverse rocking of the tool holder 4 and then the tool is retracted to permit an indexing movement of the work carrying drum. It is retracted to the extent shown in dotted lines in Figure 25 when the cam 610 is not in operating position so that on its traverse it clears the truing device as shown in Figure 25. Whenever the cam 610 is in position to prevent the full lateral movement of the tool from the work, the retracting traverse brings the grinding wheel into operative relation to the truing device, as shown in Figure 26.

In order to determine the depth of cut taken by each of the tools or grinding wheels on the work, the distance to which the truing device extends beyond the edge of its opening 715 of the ring 700 should be adjusted, and in order to facilitate this a gage such as shown at 725 in Figure 5 may be employed. This gage comprises a disk having peripheral openings 726 arranged in circular series therearound, these openings extending to different distances from the circumference of the disk. These openings are of such size that the truing devices may enter therein, the truing diamonds resting against their bases. As shown the openings are numbered to show their differing depths so that when this plate 725 is placed within one of the openings 715 of the disk member 700 with the desired openings 726 in cooperative relation to the truing device, the truing device may be adjusted until its diamond point contacts with the inner wall of the recess 726 thus to determine the extent to which it projects beyond the edge of the opening. The openings 715 are spaced accurately with reference to the work holders so that this action determines the relative limiting sizes of the truing device so that for any given extent of rocking motion imparted to the tool carrier the extent of cutting of each wheel is fixed.

It will be seen from the foregoing description that at each operative motion of the machine one piece of work is having its initial cut taken, another piece of work is having its finishing cut taken, and those intermediate are having intermediate cuts taken, each being a definite adjustable proportion of the total cut of a single machining operation. The first tool to operate on the work may therefore be of a character particularly suit-

able for operation on the hard skin of a casting. The last tool may be a finishing tool and may take a very small or light cut. It may in fact be a lap or polishing tool, while 5 intermediate tools may be of the character best suited for the particular work done by each.

Driving mechanism

10 The shaft 225 extends through the machine bed and on its rear end it is provided with a beveled gear 620 meshing with a similar gear 621 fixed to the shaft 175. This shaft 175, as was heretofore described, is driven from the shaft 137 (see Figure 9). This 15 shaft is provided with a beveled gear 650 meshing with a gear 651 on a shaft 652 which extends lengthwise through the base of the machine and carries at its opposite end a belt pulley 653. At 660 is shown a motor shaft having a belt pulley 661 about which extends a belt 662, the upper stretch of which passes beneath and partly around the pulley 653 and up and around the pulley 655 fixed to the shaft 101. From the pulley 655 this 20 belt extends about a pulley 673 and back to the motor pulley 661. The pulley 673 may be used to drive pumps for coolant or lubricant if desired. The shaft 101 is thus rotated whenever the motor is running, but the tool 25 traversing and feeding may be connected or disconnected as desired. For this purpose the gear 650 carries a clutch element 670 with which a mating clutch element 671 may be thrown by means of a hand lever 672.

Ball bearing grinder

30 In Figures 27 to 47 are shown a somewhat modified construction particularly adapted for grinding the ball tracks in outer raceway members of ball bearings, such members having internal substantially semicircular 35 grooves or tracks to receive the balls.

As shown in Figure 27, the machine comprises the headstock 800, a tool carrier 801 40 capable of reciprocating and rocking similarly to the construction previously described, and a tailstock 802 which supports the tool carrier traversing and controlling mechanism and a portion of the rotating mechanism for the work holders. There is also a 45 feeding mechanism to effect a rocking of the tool holder and truing devices for the tool. Where the machine is designed for this type 50 of work, however, certain modifications in construction are desirable. For example, there need be no traversing of the grinding wheel while in contact with the work, it being preferable to shape the grinding wheel 55 to the contour of the groove to be cut and present this wheel to the work by a single feeding motion directly theretoward. The traversing movement is therefore used only 60 for withdrawing and presenting the tool to 65 the work and also for presenting the tool

to the truing devices. The employment of two speeds for the traversing is therefore quite unnecessary since all of the traverse is effected when the grinding wheel is out of contact with the work. A modified construction of truing device is provided, also, in which the truing tools are given a motion such that the contour of the grinding wheel is dressed to that of the groove which it is to form in the work. Only those parts, therefore, which differ from the mechanism already described will be described in connection with this modified construction, except where such description seems necessary.

Traversing mechanism for ball bearing raceway grinder

This mechanism is shown more particularly in Figures 27 and 32 to 37. To effect the traversing the tool holder carrying bar is provided with circular rack teeth, as previously described, with which meshes the gear 805 on the feed shaft 806, which may be provided at its outer end with a handle as shown at 404 in Figure 17 by which it may be manually turned. On this feed shaft is fixed the worm gear 807 with which is arranged to mesh a worm 808 keyed to the sleeve 809 (see Figure 34) journaled on the axially movable shaft 810. This shaft may be moved axially by movement imparted to the collar 811 fixed to one end thereof and by such movement one or the other of the clutch collars 812 and 813 is caused to come into clutching engagement with the corresponding end of the sleeve 809, this being similar to the construction shown in Figure 20. In this machine, however, there is an intermediate position wherein the tool is not traversed, this during operation on the work and also during truing of the wheel. The clutch collars 812 and 813 are slidable axially of, but keyed to be turned by, the gears 814 and 815, these gears 814 and 815 being journaled on the sleeves 816 which hold the worm 808 against axial movement in the 95 casing 820.

The gear 814 meshes with a gear 821 fixed to a countershaft 822 positioned above and back of the shaft 810. This shaft 822 is driven by a gear 824 (Figure 36) with which 100 meshes a gear 825 keyed to a drive shaft 826 positioned directly back of the shaft 810. This drive shaft 826 also has journaled thereon a gear 827 which meshes with the gear 815. This gear 827 is also in mesh with a gear 828 on the countershaft 822. Thus the drive shaft 826 drives the countershaft 822 and this countershaft drives the gear 814 directly and the gear 815 through the intermediate loose gear 827. Thus the gears 814 and 815 are driven in opposite directions so 105 that the worm 808 may be driven in either of these directions in accordance with the axial position of the shaft 810, and will be stationary in an intermediate position of this 110

shaft. The drive shaft 826 carries a gear 830 at one end which meshes with the gear 451 on the work holder rotating shaft as heretofore described.

5 The casing 820 is pivoted on the drive shaft 826 and may be raised to bring the worm 808 out of mesh with the worm wheel by means of a handle 831 which is normally held in its lowered position with the worm in contact with the worm wheel by the spring latch 832. The axial position of the shaft 810 with the clutch collars by which the gears 814 and 815 are brought selectively into driving relation with the worm is controlled 10 by an arm 835 fulcrumed at 836 on the casing 820 and having forked extremities 837 and 838 carrying rolls riding between the flanges of the spool shaped collar 811. The forked portion 837 is extended forwardly and has 15 pivoted thereto at its outer end a link 840, the opposite end of which is pivoted at 841 to the lever 842. This lever 842 is fixed to a shaft 843 which within the casing 820 carries 20 an arm 844. Seated to slide lengthwise in this arm is a spring pressed conical plunger 845 which engages the head 846 of a pin 847 fixed in the casing. The head 846 of this pin has a central notch 848 into which the conical pin 845 may be projected when the arm 844 is in one angular position. When it is in 25 this position the arm 835 is so held by its connection to the lever 842 by the link 840 that the shaft 810 is in its mid-position with both clutch collars out of driving relation to the 30 worm 808. This is the position of the parts during the grinding action of the wheels on the work and during the truing of the grinding wheel.

By exerting a lateral pressure on the lever 10 842 this lever may be turned, the spring pin riding out from the notch 848, and the parts are so proportioned that this lever may be so turned to an extent sufficient to throw either of the clutch collars into driving relation 15 with the worm 808 without the spring pin riding completely off of the head 846. It will be noted that this lever 842 is not permitted a pivotal movement forwardly and rearwardly as is the similar lever in the construction first described. The worm gear 807 is provided with an annular slot 850 T-shaped in cross section in which are adjustably positioned two abutment pins 851 and 852, which, as the worm wheel is turned in opposite 20 directions, may strike a finger 853 projecting rearwardly from the lever 842. These parts are so designed that when either of the clutches are in operative relation to drive the worm 808, one of the pins 851 or 852 is moving toward the finger 853 as the worm gear 807 is being rotated. Such rotation continues until this pin contacts with the finger 853 and moves the lever sufficiently to bring the spring pressed pin 845 into the notch 848, whereupon 25 the clutch is disconnected from the worm and

the rotation of the worm wheel ceases. This stopping of the rotation of the worm wheel occurs at both ends of its traversing motion, at one end when it is in position to be given its feed movement into operative relation to 70 the work, and at the other end when it is in position for lateral feed to the truing device which may then act thereon. When these operations have been completed it is necessary to move the lever 842 so as to bring the proper 75 clutch into operative relation to the worm wheel 807 to start the rotation of the worm gear 808 to move the grinding wheels axially to the opposite end of the traverse. This is accomplished as shown best in Figures 27 80 and 44 by cam elements 855 fixed to a disk 856 carried by the shaft 235, which act alternately on a follower on one end of a lever 857 journaled at 858 on the machine bed. The opposite end of this lever is connected 85 through a link 859 to a bell crank lever 860 fulcrumed at 861 on the machine bed. The arm 862 of this bell crank lever is provided with a pair of spaced flanges 863 at its upper end through which are positioned adjusting screws 864 positioned on either side of a lug 865 projecting rearwardly from the lever 842. By means of these cam elements 855 the lever 842 is swung first to one side and then to the other (Figures 43 and 45) after 95 having been placed in its mid-position (Figure 44 full lines) by impingement of either of the pins 851 or 852 on its finger 853. In Figure 27 a pair of adjustable positive stops 100 are shown at 520 and 521 for positively limiting the extent of traverse of the tool holder 4 in opposite directions. The outer stop 521 may be removed from operative position, should it be desired to retract the tool carrier to an extent greater than normal, by 105 rocking the handle 522 (Figures 27 and 28) downwardly, this acting to swing the stop 521 out of operative relation to the arm 550 fixed to the tool holder, the arm 550 being actuated to feed the tools to the work as has 110 already been described.

Wheel truing mechanism for ball bearing raceway grinder

The truing devices are carried by a ring 115 member 900 (see Figure 30) having a peripheral rib 901 which rides in the annular channel 702 in the headstock 2 within which it is held in position by the retaining ring 703. As shown best in Figure 29, the ring 900 is 120 provided with openings 905 through which the several grinding wheels may pass and is provided with a cut away portion 906 arranged opposite to the work loading and unloading station. This ring 900 may be angularly adjusted relative to the headstock 2 by means of the adjusting lever 710 with its adjusting screw 711 as heretofore described, the inner end of the adjusting lever engaging 125 a notch 909 in the ring member 900. 130

Each of the diamond or truing device holders in the present construction differs from that heretofore described. In the present construction, each of these truing devices, as 5 910, being carried in a bracket 911 having a conical bearing portion 912 rockably mounted in a lug 913 projecting from the outer face of the ring member 900. The holder 911 also has an end conical bearing portion 914 which 10 is rockably journaled in a central hub portion 915 of the annular member 900 which surrounds a central opening through which the tool bar passes. The bearing portions 912 and 914 of the truing device holder 911 15 are held in close bearing relation to their respective bearing openings by means of a spring 916 bearing at one end on a collar 917 engaging the lug 913 and bearing against the hub 918 of a bevel pinion 919 pinned or otherwise fixed to the holder member 911 between the hub portion 915 and the lug 913. Each 20 of these pinions 919 meshes with an annular beveled ring gear 920 which is rotatably held within the outer portion of the hub 915 and 25 in engagement with the pinions by means of a retaining ring 921 bolted or otherwise fixed to the face of the hub member 915. This annular gear 920 may be rocked so as to cause a rocking motion of each of the truing device 30 holders 911 about the axis of its bearing portions, this axis being eccentric to the truing tool so that this tool moves in the arc of a circle of a radius equal to that which it is desired to give the grinding wheel. This radius may be adjusted by adjusting the truing 35 device axially in the holder 911.

Such rocking motion of the ring gear 920 is shown as being effected by the following mechanism. Pivoted at 925 thereto (see 40 Figure 29) is a link 926, the opposite end of which is pivoted at 927 to an arm 928. This arm is fixed to a shaft 929 (see Figure 27) journaled to the headstock, and at its opposite end it carries a forwardly directed arm 45 930 to which is pivotally connected the upper end of a rod 931. The lower end of this rod 931 is pivotally connected at 932 to a lever 933 fulcrumed at 934 on the machine bed and having a forked extremity 935 provided 50 with follower rollers 936 projecting on opposite sides of a cam member 937 carried by the shaft 235 (see Figure 47). This cam member 937 is arranged to effect a rocking motion of the lever 933 which thus imparts through 55 the connections specified a rocking motion to the ring gear 918 which causes each of the truing tools to be moved in the arc of a circle, which when the corresponding grinding wheel is presented thereto, acts to true its 60 grinding surface to a corresponding arc.

The cycle of operations of this machine is as follows. The work is presented to the work holders at the loading station and when 65 finished is removed therefrom in the same manner as heretofore described. After

passing from the loading station the work passes to each of the operating stations in sequence until the work is finished. At each operating station a grinding wheel 950 being positioned relative to the work W substantially as shown diagrammatically in Figure 70 40, the tool is given an axial traverse toward the position shown in Figure 39 in which it is in the plane of the ball receiving channel of the work which it is desired to grind. The 75 tool is then given its work feeding movement by rocking of the tool carrier 801 by a feeding mechanism similar to that heretofore described so that it is in the position shown in Figure 38. After a sufficient feed motion 80 relative to the work it is again retracted to the position shown in Figure 39 and then is drawn backwardly axially to the position shown in Figure 40. It is then given a lateral motion into the position shown in Figure 41 85 to truing position. The truing device is then moved through an arc, as shown in this figure, into the dotted line position, and is then returned to its original position whereupon the 90 tool is again moved laterally into the position shown in Figure 40 where it is prepared for a succeeding similar cycle of operations.

In Figures 42 and 46 are shown the feed cams by which the feed of the tool to the work and to the truing mechanism is effected. The 95 frame arm 601 heretofore described is moved to produce the feed motions by means of the cam 960 on the shaft 235, and the feed motions to compensate for wear and truing of the grinding wheel is effected by the cam 961 acting on the rod 585 in the manner heretofore described. The position of the parts shown in Figure 42 is that in which the tool 100 950 is grinding the work as shown in Figure 38, while the position shown in Figure 46 105 corresponds to the time when the grinding wheel is being fed from the position in Figure 40 to that of Figure 41.

Figures 43, 44 and 45 illustrate successive 110 positions of the tool traverse and controlling elements, Figure 43 showing the parts when in position for traverse in one direction, Figure 44 showing the parts when in the neutral mid-position where the tool is operating on the work or being trued, and Figure 45 showing the parts positioned for the reverse direction of traverse. Figure 47 illustrates by full and dotted lines the motion of the lever 933 when the tool is being trued.

Certain embodiments of this invention having thus been described it should be evident to those skilled in the art that various changes and modifications might be made therein without departing from the spirit or scope of this invention as defined by the appended 120 claims.

I claim:

1. A machine of the class described comprising a plurality of work holders, a tool 125 for operating on work carried by each of 130

certain of said work holders, means for moving said holders and tools relatively step by step to bring work on each holder into position to be operated on by each of said tools in succession, and means for effecting simultaneous operative movements of all of said tools relative to said holders in the line of said step by step movement each on work carried by the work holder then in operative relation thereto.

2. A machine of the class described comprising a drum, a plurality of work holders carried by said drum and arranged in circular series, a tool holding member, a plurality of tools carried by said member in circular series, means for moving said drum and member relatively axially to bring each of said tools into and out of cooperative position with the work carried by one of said holders, means for relatively turning said drum and member when the tools are in such position to feed the tools about the turning axis against the work and to retract them therefrom, and means acting when said tools are out of cooperative position with the work for causing a relative turning of said drum and member to position each tool to operate on a different piece of work during the succeeding tooling operation.

3. A machine of the class described comprising a rotatable drum, a plurality of work holders arranged in circular series about the axis of rotation of said drum, means for rotating said drum step by step to bring the work holders successively into the same position, a tool holding member, a plurality of tools carried by said member arranged in circular series, each tool being positioned substantially in line with one of said work holders when said drum is stationary, means for moving said member axially of said drum to bring said tools simultaneously into and out of the plane of the work carried by said holders, and means for rocking said member about said axis to impart simultaneously feed and retracting movements to all of said tools about said axis.

4. A machine of the class described comprising a rotatable drum, a plurality of rotatable work holders arranged in circular series in said drum with their axes of rotation parallel to the axis of rotation of said drum, means for indexing said drum to bring said work holders in succession into the same position, a tool holder, a plurality of tools carried by said holder arranged in circular series each substantially in alinement with one of said work holders when said drum is stationary, means for moving said tool holder axially of said drum, and means for rocking said tool holder to effect feed and retracting motions about the rocking axis relative to the work when said tools are in the axial position therefor.

5. A machine of the class described com-

prising a drum, a plurality of work holders arranged in circular series in said drum, a tool holding member, a plurality of rotary tools carried by said member in circular series each substantially in line with one of said work holders, means for rotating each of said tools, means for reciprocating said member toward and from said drum, and means for rocking said member to effect feed and retracting motions about the rocking axis of said tools relative to work carried by said work holders.

6. A machine of the class described comprising a drum, a plurality of work holders arranged in circular series in said drum, a tool holder, a plurality of tools arranged in circular series each tool being substantially in line with a work holder there being one less tool than work holders, means for rotating said work holder and drum relatively step by step to present said work holders successively into line with each tool, one of said work holders having no tool in operative relation at each step, means for moving said drum and tool holder at each step into and out of position for each tool to operate on the work on that work holder in line therewith, means to feed and retract the tools relatively to the work by rotation about the axis of rotation of said drum when in such position, and means acting at each step to remove tooled work from said one work holder and to present untooled work thereto.

7. A machine of the class described comprising a rotatable drum, a plurality of work holders arranged in circular series in said drum, a tool holder, means for rotating said drum step by step to present each work holder in succession in one position, a plurality of tools arranged in circular series in said tool holder, each tool being substantially in line with one work holder when said drum is stationary, there being one less tool than work holders, and one position of each work holder without a tool in substantial alinement therewith constituting a work ejecting and loading position, means to reciprocate said tool holder axially of said drum to bring said tools simultaneously toward and from work carried by said work holders, means for rocking said tool holder about said axis to cause feed and retraction of said tools about the rocking axis relative to the work, and means acting at said work ejecting and loading position to eject tooled work from the work holder at said position and to supply untooled work thereto after each step by step movement of said drum.

8. A machine of the class described comprising a rotatable drum, a plurality of rotatable work holders arranged in circular series in said drum, means for rotating said work holders, means for rotating said drum step by step to present each work holder in succession in one position, a tool holder, a

- plurality of tools arranged in circular series in said tool holder, each tool being substantially in line with a work holder when said drum is stationary, there being one less tool than work holders, and one position of each work holder without a tool in substantial alinement therewith constituting a work ejecting and loading position, means to reciprocate said tool holder axially of said drum to bring said tools simultaneously toward and from work carried by said work holders, means for rocking said tool holder about said axis to cause feed and retraction of said tools relative to the work about the rocking axis, and means acting at each stopping of said drum at the work ejecting and loading position to stop the rotation of the work holder in said position, to eject tooled work therefrom, to supply untooled work thereto, and then to start the rotation of said holder.
9. A machine of the class described comprising a bed having a headstock and a tailstock, a drum rotatably mounted in said headstock on an axis extending toward said tailstock, a plurality of work holders arranged in circular series in said drum, each rotatable on an axis parallel to the axis of said drum, a rotatable shaft extending axially of said drum journaled in said drum and in said tailstock, rotating connections from said shaft to each of said work holders, a hollow bar through which said shaft passes slidably journaled in said drum and tailstock, a tool holder fixed to said bar between said drum and tailstock, a plurality of tools carried by said tool holder in circular series corresponding to that of the work holders, means carried by said tailstock for traversing said bar to move said tools toward and from work carried by said work holders, means for rocking said tool holder about the axis of said bar to impart simultaneous feed and retracting movements to all of said tools relative to the work, and means for rotating said drum step by step to bring the work holders in succession into position to have work carried thereby acted on by each tool.
10. A machine of the class described comprising a drum, a plurality of work holders arranged in circular series in said drum, a tool holder, a plurality of tools carried by said holder in circular series, means for moving said tool holder to move each of said tools from and toward one of said work holders, means for rocking said tool holder to impart feed and retracting movement of said tools relative to the work, means for dressing said tools, and means for advancing said tools relative to said rocking means after the tools have been dressed to make up in the rocking feed motion for the material removed therefrom by the truing operation.
11. A machine of the class described comprising a rotary drum, a plurality of work holders carried by said drum and arranged

in circular series, a tool holder, a plurality of tools carried by said tool holder and arranged in circular series, means for reciprocating said tool holders toward and from work carried by said work holders, means for rotating said drum step by step to bring each work holder successively opposite to each tool, a member positioned between said drum and tool holder, and tool truing devices for all of said tools carried by said member.

12. A machine of the class described comprising a member, a plurality of work holders carried by said member, a tool holder, a plurality of tools carried by said tool holder each tool being positioned opposite to a work holder, a plate member positioned between said work holder carrying member and said tool holder and having openings in line with said work holder and tools, means to move said tool holder to project said tools through said openings and into cooperative relation with work in said work holders, and tool dressing devices carried by said plate member at said openings.

13. In a machine of the class described, a rotatable drum, a plurality of mechanisms arranged in circular series in said drum, means for rotating said drum, a plurality of stop elements carried by said drum, and an abutment movable into and out of the path of movement of said elements and by which the rotation of said drum may be stopped by impingement of any of said stop elements thereon, means for rotating said drum in the reverse direction sufficiently to relieve the pressure of a stop on said abutment, and means acting while said pressure is relieved for moving said abutment out of stopping position.

14. In a machine of the class described, a rotatable drum, a plurality of mechanisms arranged in a circular series in said drum, a worm gear carried by said drum, an axially movable shaft, a worm carried by said shaft and meshing with said worm gear, a clutch comprising a pair of interengaging elements one of which is fixed to said shaft and is movable into and out of engagement with the other by the axial movement of said shaft, a spring for pressing said shaft into clutching position, a plurality of stops on said drum, an abutment, means for moving said abutment from and toward a position to be engaged by said stops in succession to stop the rotation of said drum in predetermined angular positions, and means for driving said other clutch element in a direction to cause engagement of said worm on said worm wheel when the drum is held from rotation to move said shaft axially into unclutched position.

15. In a machine of the class described, a rotatable drum, a worm gear carried by said drum, an axially movable shaft, a worm carried by said shaft and meshing with said worm gear, a clutch comprising a pair of in-

- terengaging elements one of which is fixed to said shaft and is movable into and out of engagement with the other by the axial movement of said shaft, a spring for pressing said shaft into clutching position, a stop on said drum, an abutment movable from and toward a position to be engaged by said stop to stop the rotation of said drum, means for driving said other clutch in a direction to cause engagement of said worm on said worm wheel when the drum is held from rotation to move said shaft axially into unclutched position, means for imparting a reverse rotation to said drum when said abutment is to be moved from stopping position sufficient to relieve the pressure of said stop thereon, and means acting while such pressure relieved to move said abutment out of said position.
16. A machine of the class described, comprising a member, a plurality of work holders carried by said member, a tool holder, a plurality of tools carried by said tool holder, each tool being positioned opposite to a work holder, a plate member positioned between said work holder carrying member and said tool holder and having openings in line with said work holders and tools, means to move said tool holder to project said tools through said openings and into cooperative relation with work in said work holders, tool dressing devices carried by said plate member at said openings, and means for effecting relative motion between said tool holder and plate to bring such devices into and out of dressing position with respect to their respective tools simultaneously to true said tools as they pass through said openings.
17. In a machine of the class described, a rotatable drum, a plurality of work holders arranged in circular series about the axis of rotation of said drum, a shaft mounted for rotation and axial movement coaxially with the axis of rotation of said drum, a tool holder fixed to said shaft, tools carried by said holder in circular series corresponding to said work holders, means for indexing said drum to bring each work holder successively into substantial alinement with each tool, means for traversing said shaft when said drum is in indexed position to effect operative traverses of each tool on the work in substantial alinement therewith, and means to rock said holder to effect simultaneous feed and retraction of all the tools relative to work in the several work holders.
18. In combination, two members, means for supporting both of said members for rotation about a common axis and for supporting one of said members for movement longitudinally of said axis from and toward the other of said members, a plurality of work holders arranged in circular series about said axis and carried by one of said members, and a plurality of tools arranged in circular series and carried by the other of said members in position to operate on work held by said holders.
19. In combination, two members, means for supporting said members for relative rotation about an axis and for relative motion toward and from each other lengthwise of said axis, rotary work holders arranged in circular series in one of said members with their rotating axes parallel to the axes of said members, rotary tool spindles arranged in circular series in said other member corresponding to the series of work holders, said tool spindles being journaled in fixed position in said other member with their rotational axes parallel to the axes of said members, and a tool carried by each spindle.
20. A machine of the class described, comprising a tool holder, a plurality of tools carried by said holder and arranged in circular series, a plate having openings arranged in circular series corresponding to said tools, means for moving said holder and plate relatively to project and withdraw said tools through said openings, a tool dressing device positioned at each of said openings, and means for relatively rocking said holder and plate about the axes of said series to bring all of said devices simultaneously into and out of operative relation to said tools as they are passed through said openings.
21. A machine of the class described, comprising a tool holder, a plurality of tools carried by said holder and arranged in circular series, a plate having openings arranged in circular series corresponding to said tools, means for moving said holder and plate relatively to project and withdraw said tools through said openings, a tool dressing device positioned at each of said openings, and adjustable relative thereto, and means for relatively rocking said holder and plate about the axis of said series to bring all of said devices simultaneously into and out of operative relation to said tools as they are passed through said openings.
22. A machine of the class described, comprising a tool holder, a plurality of tools carried by said holder and arranged in circular series, a plate having openings arranged in circular series corresponding to the tools, means for moving said holder and plate relatively to project and withdraw said tools through said openings, a tool dressing device carried by said plate and positioned at each of said openings, means for rocking said holder, and means for angularly adjusting said plate about said rocking axis to simultaneously vary the relations of all of said devices to their respective tools for any rocked position of said holder.
23. A machine of the class described, comprising a tool holder, a plurality of tools carried by said holder, a tool dressing device carrier, a plurality of tool dressing devices on

said carrier, and means for adjusting said carrier relative to said holder to effect simultaneous adjustment of all of said devices relative to their respective tools.

5 24. A machine of the class described, comprising a plurality of tools, a plurality of tool dressing devices for said tools, and means for supporting said dressing devices relative to said tools with capability of independent and simultaneous adjustment of said devices relative to their respective tools.

10 25. A machine of the class described, comprising a pair of members, a plurality of work holders carried by one of said members, a plurality of tools carried by the other of said members, a carrier between said members, tool dressing devices on said carrier, means for moving said members relatively to effect work feeding and retractive movements of said tools relative to said work holders, and to effect tool dressing movements of said tools relative to said devices, and means for moving said carrier to simultaneously adjust the truing action of all of said devices relative 20 to said tools for any given dressing movement of said tool carrier.

25 26. A machine of the class described comprising a pair of members, a plurality of work holders carried by one of said members, a plurality of tools carried by the other of said members, a carrier between said members, tool dressing devices on said carrier, means for moving said members relatively to effect work feeding and retractive movements of 30 said tools relative to said work holders, and to effect tool dressing movements of said tools relative to said devices, means for moving said carrier to simultaneously adjust the truing action of all of said devices relative 35 to said tools for any given dressing movement of said tool carrier, and means for adjusting each of said devices independently of the others relative to said carrier.

40 27. A machine of the class described comprising a holder, a plurality of spindles journaled in parallel relation in circular series in said holder, a grinding wheel on each spindle, a carrier adjacent to said holder, and movable relative thereto and having a plurality of openings through which 45 said grinding wheels may be projected on such relative movement between said holder and carrier, and a wheel dressing device on said carrier at each opening, means for carrying said devices permitting each to be rocked to describe a curved path, and means for simultaneously rocking all of said devices when said holder and carrier are so relatively positioned that such devices may 55 act on said wheels.

60 28. A machine of the class described comprising a holder, a plurality of spindles journaled in parallel relation in circular series in said holder, a grinding wheel on 65 each spindle, a carrier adjacent to said

holder, and movable relative thereto and having a plurality of openings through which said grinding wheels may be projected on such relative movement between said holder and carrier, and a wheel dressing device on 70 said carrier at each opening, means for carrying said devices permitting each to be rocked to describe a curved path, means for simultaneously rocking all of said devices when said holder and carrier are so relatively 75 positioned that such devices may act on said wheels, and means for rocking said carrier relative to said holder about the axis of said circular series to effect simultaneous adjustments of all of said devices relative to their 80 respective wheels.

29. A machine of the class described comprising a plurality of rotatable work holders arranged in circular series, a tool for operating on work carried by certain of said holders, means for moving said work holders and tools relatively step by step to present work on each holder into position to be operated upon by each of said tools in succession, means for rotating said holders, and means for simultaneously moving certain of said tools laterally of the axis of work in operative relation thereto to effect relative feed and retraction therebetween.

In testimony whereof I have affixed my 95 signature.

WILLIAM L. BRYANT.
